UNITED STATES PATENT OFFICE.

JOHN PRIMROSE, OF DONGAN HILLS, NEW YORK.

SUPERHEATER.

1,157,722.

Specification of Letters Patent.

Patented Oct. 26, 1915.

Application filed October 28, 1914. Serial No. 868,944.

To all whom it may concern:

Be it known that I, JOHN PRIMROSE, a subject of the King of Great Britain, residing at Dongan Hills, county of Richmond, State of New York, have invented certain new and useful Improvements in Superheaters, of which the following is a full, clear, and exact description.

The invention which constitutes the subject matter of the present application for Letters Patent is an improvement in steam superheaters, particularly for vertical water tube boilers of the ordinary type. It has been the common practice for a long period in the installation of superheaters in boilers of this general form to place the superheater back of the first bank of tubes, as the space there provided is not only convenient and accessible for the purpose, but affords the best conditions for superheating the steam. The specific type of superheater used in this location may be, and in practice has been, widely varied, and most, if not all, known forms have been used indifferently, among these the Niklausse superheater supported by its ends in the walls of the furnace structure, and the inverted U-tube type, supported either by its header in the same walls, or by straps or hangers depending from the beams which are used for supports for the boiler drums in constructions of this character.

I have endeavored to improve upon the constructions heretofore used and to produce a simpler form of superheater that may be supported within its allotted space more economically and effectively than heretofore which, in connection with the novel baffling arrangement, will yield a better result in its output of superheated steam than the usual forms by providing a novel method of diverting the gases in passing over the same. This baffling is so arranged that the extreme heat of the furnace does not come in direct contact with the headers forming a part of the superheater.

According to my present invention I install the superheater in what would ordinarily be the second pass of the boiler, but by virtue of the specific baffling the superheating units and the upper header are located in the first pass of the boiler and the lower header is located in the second pass of the boiler. The form of superheater which I employ is preferably of V-shape, that is to say, composed of double series of

legs or sets of tubes expanded into a longitudinal header or tube extending across the furnace and expanding or spreading in the form of a letter V. This superheater is supported by its legs or tubes, preferably by expanding the ends of the two sets directly into an upper header which is supported by means of beams which, in boilers of this type, are used as supports for the drums.

From the above it will be apparent that one feature of my invention specifically stated, consists in providing a superheater between the first and second banks of boiler tubes, and a baffle for the first bank of tubes stopped off at an intermediate point and having a portion continued up at the rear of the superheater whereby the furnace gases after leaving the first bank of tubes are deflected among the superheater units and among the boiler tubes of the second bank.

In the drawing hereto annexed I have illustrated so much of an ordinary boiler setting and the superheater above described as is necessary to an understanding of my invention. The figure shown in this drawing is a vertical sectional view of the invention illustrating all of the essential parts thereof.

The boiler proper is of any ordinary type, generally characterized by upper drums 1, connected with a lower drum 2 by substantially vertical banks of tubes 3, 4 and 5. In such boilers there are usually placed baffle plates 6 and 7 to deflect the gases and confine their action to the banks of water tubes, and steel or iron beams 8 (only one being shown in the drawing), extending transversely across the boiler setting to furnish supports for the upper drums. I have not illustrated herein the usual chairs intermediate to these beams and the drums as these are usually placed outside the walls of the setting.

The superheater is composed of sets of tubes 9 and 10 united at their lower ends to a transverse saturated steam header 11 connected, by means of the pipe 12, directly with one or more of the steam drums 1 and connected at their upper ends to a second header 13. The header 13 is, by preference, supported on a strap to the beams 8, which, as above stated, are usually employed in boilers of this type to support the drums. The arrangement just described provides for greater flexibility and renders the expanded joints more accessible and remove

such joints and headers from the direct current of incandescent gases.

One of the important features of my invention relates to the construction of a boiler baffle which is stopped off at the level of the top of the lower or inlet superheater header and is carried as indicated at 14 to the back of the superheater elements and continued up at the rear of the same, as indicated at 15. This exposes all of the superheater surface uniformly to the gases and at the same time forces the gases, without the use of a shelf baffle or other means, into the second bank of boiler tubes. In boilers of this type, without a superheater, it is customary to provide what is known as shelf baffles running at right angles through the baffle on the first bank of tubes at a point a little above the lower superheater header and extending over substantially to the second bank of boiler tubes for the purpose of diverting the gases and causing them to flow among the tubes of the second bank. Where superheaters are installed in boilers of this type this shelf baffle has had to be abandoned and the superheater headers, when arranged at the bottom of the superheater, takes the place of this baffle to a certain extent. The arrangement, however, of baffling which I have described herein and shown in the annexed drawing is better than is possible with the ordinary arrangement of superheater and is even superior to the shelf baffle for the purpose of forcing the gases among the tubes of the second bank.

Other modifications and forms will be understood without specific description or illustration. For instance, it is quite obvious that the specific form of superheater shown and described is subject to innumerable modifications without in any way deviating from the true scope of my invention. The same is true as regards the specific form of connection shown and described between the boiler drums and the superheater headers. It will therefore be understood that the specific form of my invention shown herein is merely for illustrative and descriptive purposes only and that I do not limit myself in any way except by the limitations imposed by the appended claims.

What I claim is:—

1. The combination of a boiler of the ordinary type, of a superheater located between the first and second banks of water tubes comprising upper and lower headers and superheating units connecting said headers, each of said units consisting of two portions bent at substantially right angles to each other to afford access to the superheater and to permit freedom of expansion of said superheater, and a baffle for the first bank of tubes therein stopped off at the level of the top of the lower or inlet superheater

header and carried to the back of the same and continued up at the rear of the superheater.

2. The combination with a boiler of the usual type; of a baffle for the first bank of tubes offset at an intermediate portion and continued upwardly from the offset to deflect the gases from the first pass among the tubes of the second pass; and a superheater comprising upper and lower headers and superheating units connecting said header, each of said units consisting of two portions bent at substantially right angles to each other to afford access to the superheater and to permit freedom of expansion of said superheater, the lower or inlet header located in the second pass of the boiler, and the outlet header and superheating units located between the upwardly continued portion of the baffle and the first bank of water tubes. 85

3. The combination with a boiler having a plurality of banks of tubes therein, of a superheater located between the first and second banks of tubes therein comprising two horizontal headers and superheating tubes connecting said headers, one of said headers being arranged above the superheating tubes and the other of which is arranged below the superheating tubes, one of said headers being an inlet to and the other an outlet from the superheater tubes, said superheating tubes consisting of two rows transversely arranged with respect to the flow of furnace gases through the boiler and provided with horizontal portions extending laterally from both sides of the upper header, whereby access between the two rows of superheating tubes is afforded and freedom from rigid resistance to expand by heat is permitted. 100

4. The combination with a boiler having a plurality of banks of water tubes therein, of a superheater located between the first and second banks of tubes comprising horizontally arranged inlet and outlet headers, and two vertical rows of superheating tubes transversely arranged in said boiler and connecting the lower header at the top and each row provided with horizontal portions connected to the upper header at the opposite sides thereof, whereby access is afforded between the two rows of tubes,—and freedom of expansion of said tubes is permitted. 110

5. The combination with a boiler having a plurality of banks of water tubes therein, of a superheater located between two of said banks comprising horizontally arranged inlet and outlet headers, and two rows of superheating elements transversely arranged in said boiler, each of said elements consisting of two portions arranged at substantially right angles to each other with the lower portion connected to the lower header and the upper portion connected to the upper header. 125

6. The combination with a boiler having a plurality of banks of water tubes therein, of a superheater located between two of said banks comprising horizontally arranged inlet and outlet headers, and a row of superheating elements transversely arranged in said boiler, each of said elements consisting of two portions arranged at substantially right angles to each other to afford access to the superheater and to permit freedom of expansion of the elements, one of said portions connected to the lower header and the other to the upper header. 20
7. The combination with a boiler having a plurality of banks of tubes therein, of a superheater located between the first and second banks of tubes therein comprising two horizontal headers and superheating tubes connecting said headers, one of said 25
- headers being arranged above the superheating tubes and the other of which is arranged below the superheating tubes, one of said headers being an inlet to and the other an outlet from the superheating tubes, said superheating tubes being transversely arranged with respect to the flow of furnace gases to the boiler and provided with horizontal portions connected to and extending laterally from one of said headers, whereby access to the superheater is afforded and 30 freedom from rigid resistance to expand by heat is permitted. 30

In testimony whereof I affix my signature in the presence of two subscribing witnesses.

JOHN PRIMROSE.
